BORING MACHINE

Cleo R. Ivey, Jasper, Ala.

Application January 10, 1951, Serial No. 205,329

10 Claims. (Cl. 255—20)

1

This invention relates to new and useful improvements in drilling machines and the primary object of the present invention is to provide a machine for drilling holes under pavement or concrete so that pipe lines may be placed under the street without breaking the pavement or concrete.

Another important object of the present invention is to provide a drilling machine that may be lowered to and from any depth up to four feet without the necessity of submerging the machine into a ditch.

Yet another object of the present invention is to provide a drilling and boring machine including a wheeled frame and a vertically swingable auger support disposed below the frame and movable up to the frame to permit the frame to be transported in a convenient manner.

A further object of the present invention is to provide a boring machine including a wheeled frame and novel and improved corner jacks at the ends of the frame whereby the frame may be raised to a predetermined height.

A still further aim of the present invention is to provide a portable drilling apparatus that is extremely efficient and reliable in use, strong and durable in operation, compact in structure, inexpensive to manufacture, service and operate, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view of the present invention in use;

Figure 2 is a side elevational view of the present invention in use and with part of the frame and carriage broken away to show the manner in which the auger support is pivoted to the carriage;

Figure 3 is a top plan view of Figure 1;

Figure 4 is a side elevational view of the present invention in position for transporting;

Figure 5 is a fragmentary side elevational view of the present invention and showing the carriage moved to the forward end of the wheeled frame;

Figure 6 is a plan view of the invention and with parts of the side beams broken away for the convenience of explanation;

Figure 7 is an enlarged detail view partly in section and partly in elevation showing the manner in which the auger is connected to the transmission; and

2

Figure 8 is a perspective view of the crank handle used in the invention.

Referring now to the drawings in detail, wherein for the purpose of illustration, there is disclosed a preferred embodiment of the present invention, the numeral 10 represents an elongated wheeled frame including a pair of spaced parallel channel-shaped side beams 12 whose forward and rear ends are connected to each other by transverse beams 14 whereby the shape of the main portion of the frame will be substantially rectangular.

A transverse axle 16 is disposed at the rear of the frame and supports rubber-tired wheels 18. The beam 14 at the forward end of the frame 10 supports a mounting plate 20 to which there is secured a rotatable and removable front wheel mount 22. A draw bar 24 is pivotally attached to the mount 22.

The forward and rear ends of the side beams 12 fixedly support vertical guides 26 in which tubular uprights 28 are slidably received. The lower ends of the uprights 28 support pressure plates 30 and the upper ends of the uprights 28 support guide pulleys 32 over which cables 34 are trained. Forward and rear cable drums 36 and 38 are mounted on the frame 10 adjacent the guides 26. The cables 34 are terminally attached to the drums and to anchor eyes 40 fixed to the side beams 12.

The drums 36, 38 each carry a ratchet 42 and the ratchets 42 underlie pawls or locking dogs 44 that are pivoted to the frame 10. Cylindrical studs 46 project horizontally from the frame 10 and these studs are so located that one stud will be disposed parallel to the axis of each drum 36, 38 and relatively close thereto. A crank handle 48 is provided for selectively rotating the drums 36, 38. One end of the crank handle 48 supports a gear 50 that will mesh with a selected one of the ratchets or gears 42 and this end of the crank handle is also provided with a socket that will receive a selected one of the studs 46.

Each of the uprights 28 is provided with a plurality of vertically spaced apertures 52. Pins 54 are received in selected apertures 52 and rest upon the guides 26 and the side beams 12 to retain the uprights vertically adjusted in the guides 26 after the uprights have been moved by rotating the drums 36, 38.

A carriage or framework 56 is mounted on the frame 10 for sliding movement and includes rollers or wheels 58 that track in the side beams 12. The carriage 56 supports a power plant 59, preferably a diesel engine, whereby an auger 60 may be rotated.

Means is provided for moving the carriage between the ends of the frame 10. This means consists of a transverse roller or drum 62 that is disposed at the rear end of the frame 10 and which is rotatably supported on a pair of vertically disposed channel-members 64 that are fixed at their lower ends to the rear ends of the side beams 12. The forward of the transverse beams 12 supports a pulley 66 over which there is trained a cable 68 that is terminally secured to the drum 62 and the carriage 56. A pair of cables 70 are terminal fixed to the rear portion of the carriage 56 and the drum 62.

An upper and lower pair of telescoped shafts 72 and 74, each composed of two sections connected by splines, are rotatably mounted on the upper ends of the channel-members 64. The upper shaft 72 supports a sprocket 76 that is connected to a sprocket 78 on the drum 62 by a sprocket chain 80. One end 74a of the shaft 74 projects outwardly from one of the members 64 and supports a pinion 82 that will mesh with the gear 50 on the crank handle 48. The socketed end of the crank handle 48 receives one end of a stud 84 that projects outwardly from one of the members 64. A gear connection is provided between the shafts 72 and 74 so that the same will rotate in unison.

A vertically swingable support 88 is secured to and depends from the carriage 56 and includes forward and rear frame members 90 and 92 that are pivoted at their upper ends to the carriage, as at 91. The lower ends of the frame members 90 and 92 pivotally support a platform 94 on which there is mounted a well-known transmission 96 whose driven shaft supports a multiple pulley 98 that is connected to a multiple pulley 100 on the drive shaft of the power plant 59 by a plurality of pulley belts 102. A diagonal brace 104 is pivoted at its upper end to the frame member 92 and the lower end of the brace 104 terminates in a hook 106 for engaging a pin 108 at the lower end of the member 90 to prevent swinging movement of the support 88.

A cable drum or roller 110 is disposed transversely of the frame 10 and is slidably and rotatably mounted on the side beams 12. A cable 112 is terminally fixed to the drum 110 and the forward end of the support 88. A crank handle 114 is fixed to one end of the drum 110 whereby the drum may be rotated to wind the cable 112 thereon and raise the support 88 when the hook 106 is removed from the pin 108.

The driving shaft of the transmission 96 supports a flexible coupling 116 including a splined sleeve 118 that received the splined end 120 of a socket member 122. The outer end of the member 122 is formed with a multi-sided recess or socket 124 in which the multi-sided end 126 of the auger 60 is held by a set screw 128.

In practical use of the present invention, the machine is pulled by a towing vehicle over a ditch D and a plank P is placed over the ditch and beneath the plates 30 of the rear uprights and a pair of blocks B are placed under the plates 30 of the forward uprights.

The uprights 28 are then lowered by the crank handle 48 or by releasing the dogs 44 and then rotating the drums 36 by the crank handle 48 until the frame 10 has been lifted a desired height. Then the pins 54 are inserted into place.

The drum 110 is rotated to lower the support 88 and the auger 60 after which the hook 106 is engaged with the pin 108 to hold the support 88

against swinging movement. The shift lever L of the transmission is in neutral. The crank handle 48 is employed as the starting crank for the power plant and is manually engaged with the starting shaft S of the power plant and is actuated to start the power plant after which the lever L is moved to drive the auger forwardly. As the auger digs into the dirt and moves forwardly, the carriage 56 also moves forwardly. When the lever L is shifted to its reverse position, the auger will move rearwardly causing the carriage 56 to move rearwardly on the frame 10.

Having described the invention, what is claimed as new is:

1. A drilling machine comprising an elongated horizontal frame, vertically adjustable uprights at the ends of the frame for supporting the frame at a predetermined height over a ditch, means mounted on the frame and operatively connected to the uprights for selectively raising and lowering the uprights, a carriage slidably carried by the frame, a vertically swingable support structure pivotally mounted on the carriage and depending from the carriage, an auger rotatably carried by the support structure and underlying and substantially parallel to the frame, means mounted on the frame and connected to the support structure for selectively raising and lowering the support structure relative to the frame, power means on the carriage operatively connected to the auger for rotating the auger, means connected to the support structure holding the latter against swinging movement, said carriage being movable horizontally on said frame, and means on the frame connected to the carriage for moving the latter horizontally back and forth on the frame.

2. A drilling machine comprising an elongated horizontal frame, vertically adjustable uprights at the ends of the frame for supporting the frame at a predetermined height over a ditch, means mounted on the frame and operatively connected to the uprights for selectively raising and lowering the uprights, a carriage slidably carried by the frame, a vertically swingable support carried by the carriage and depending from the frame, an auger rotatably carried by the support and underlying the frame, means mounted on the frame and connected to the support for selectively raising and lowering the support relative to the frame, power means on the carriage operatively connected to the auger for rotating the auger, and means connected to the support holding the latter against swinging movement, said means connected to the support for selectively raising and lowering the support including a roller extending transversely across the frame, said roller being slidably and rotatably supported on the frame, and a cable terminally secured to said support and said roller.

3. A drilling machine comprising an elongated horizontal frame, vertically adjustable uprights at the ends of the frame for supporting the frame at a predetermined height over a ditch, means mounted on the frame and operatively connected to the uprights for selectively raising and lowering the uprights, a carriage slidably carried by the frame, a vertically swingable support carried by the carriage and depending from the frame, an auger rotatably carried by the support and underlying the frame, means mounted on the frame and connected to the support for selectively raising and lowering the sup-

port relative to the frame, power means on the carriage operatively connected to the auger for rotating the auger, and means connected to the support holding the latter against swinging movement, said means for selectively raising and lowering said uprights including a plurality of cable drums mounted on the frame, a pulley on the upper end of each upright, and cables terminally attached to said frame and said drums and extending over the pulleys.

4. A combination of claim 3 and a ratchet rotatable with each drum, and a pawl for each ratchet, said pawls being pivoted to the frame.

5. A drilling machine comprising an elongated horizontal frame, vertically adjustable uprights at the ends of the frame for supporting the frame at a predetermined height over a ditch, means mounted on the frame and operatively connected to the uprights for selectively raising and lowering the uprights, a carriage slidably carried by the frame, a vertically swingable support carried by the carriage and depending from the frame, an auger rotatably carried by the support and underlying the frame, means mounted on the frame and connected to the support for selectively raising and lowering the support relative to the frame, power means on the carriage operatively connected to the auger for rotating the auger, and means connected to the support holding the latter against swinging movement, said support including forward and rear vertically swingable frame members, said means holding the support against swinging movement, includes a diagonal brace pivoted to one of the frame members and removably secured to the other frame member.

6. A drilling machine comprising an elongated horizontal frame, vertically adjustable uprights at the ends of the frame for supporting the frame at a predetermined height over a ditch, means mounted on the frame and operatively connected to the uprights for selectively raising and lowering the uprights, a carriage slidably carried by the frame, a vertically swingable support carried by the carriage and depending from the frame, an auger rotatably carried by the support and underlying the frame, means mounted on the frame and connected to the support for selectively raising and lowering the support relative to the frame, power means on the carriage operatively connected to the auger for rotating the auger, and means connected to the support holding the latter against swinging movement, said power means being mounted on the carriage, and means on the frame and connected to the carriage for moving the carriage longitudinally of the frame and between the ends of the frame.

7. The combination of claim 6 wherein said carriage moving means includes a drum disposed transversely of the frame at one end of the frame, a pulley at the other end of the frame, and a cable trained over the pulley and terminally secured to the roller and the carriage.

8. A boring machine comprising an elongated wheeled frame including a pair of channel-shaped side beams, jack means at the ends of

the frame for raising the frame and the wheels of the frame and for supporting the frame in a horizontal position, a carriage including wheels tracking in said side beams, means mounted on the frame and connected to the carriage for moving the carriage between the ends of the frame, a support depending from the carriage, a rotary auger underlying and paralleling the frame and mounted on said support, and power means on the carriage and operatively connected to the auger for rotating the auger, said jack means including a vertical guide at each corner of the frame, an upright slidably received in each guide, a plurality of cable drums rotatably mounted on said frame, a guide pulley at the upper end of each upright, cables trained over said pulleys and terminally secured to said drums and said frame, individual locking means for each drum, each of said uprights having a plurality of vertically spaced apertures and pins received in selected apertures and resting on said guides to retain the uprights adjusted in the guides.

9. A boring machine comprising an elongated wheeled frame including a pair of channel-shaped side beams, jack means at the ends of the frame for raising the frame and the wheels of the frame, a carriage including wheels tracking in said side beams, means mounted on the frame and connected to the carriage for moving the carriage between the ends of the frame, a vertically swingable auger support, means pivotally mounting the support on the carriage, means slidably and rotatably mounted on the side beams and connected to the support for selectively raising and lowering the support, and means connected to the support preventing swinging movement thereof.

10. A boring machine comprising an elongated wheeled frame including a pair of channel-shaped side beams, jack means at the ends of the frame for raising the frame and the wheels of the frame, a carriage including wheels tracking in said side beams, means mounted on the frame and connected to the carriage for moving the carriage between the ends of the frame, a vertically swingable support, means pivotally mounting the support on the carriage, a power driven auger mounted on the support, means slidably and rotatably mounted on the side beams and connected to the support for selectively raising and lowering the support and the auger, said support including forward and rear vertically swingable frame members, and a diagonal brace pivoted to one of the frame members and detachably secured to the other frame member for locking the frame members against pivotal movement.
